UNITED STATES PATENT OFFICE.

CLARK J. SMITH, OF OTTUMWA, IOWA.

PNEUMATIC ROCK-DRILL.

1,119,198.

Specification of Letters Patent.

Patented Dec. 1, 1914.

Original application filed April 7, 1913, Serial No. 759,538. Divided and this application filed May 29, 1913.
Serial No. 770,586.

To all whom it may concern:

Be it known that I, CLARK J. SMITH, residing at Ottumwa, in the county of Wapello and State of Iowa, have invented certain 5 new and useful Improvements in Pneumatic Rock-Drills, of which the following is a specification.

This invention, which relates to improvements in rock drills, is more especially in 10 the nature of a pneumatically actuated rotating attachment for pneumatic drills of the hammer type and more especially adapted for drilling coal rock and any hard mining substance. 15 In pneumatic rock drilling machines now in general use, where a reciprocating hammer piston, by rapidly successive blows, drives the drill bit farther into the substance being drilled, constant turning of the drill, 20 is necessary so that the cutting or penetrating portions on the end of the drill do not strike on the same indentations, which usually causes either a poor cutting or drilling 25 or none at all.

My invention primarily seeks to provide certain improvements in rock drills of the general type stated of a simple and practical construction and with that and other objects in view my invention consists of the peculiar 30 combination and novel arrangement of the parts, hereinafter fully described, specifically pointed out in the appended claims and illustrated in the accompanying drawings, in which:

Figure 1 is a longitudinal section, partly in elevation, of a pneumatic rock drill hammer showing my appliance attached thereto. Fig. 2 is an enlarged section on line 2—2 on Fig. 1. Fig. 3 is a view similar to Fig. 2, 40 showing the parts in a different position. Fig. 4 is a section on line 4—4 on Fig. 3. Fig. 5 is a perspective view of the pawl carrying and actuating block piston. Fig. 6 is a perspective view partly in section of the 45 precipitating air valve.

In the practical application of my present invention my improved attachments are adapted for being mounted upon and combined with a hand machine in which is included a pneumatically actuated driving member or hammer, such a general type of machine being shown in the accompanying drawings in which—

a designates the handle that carries the casing *b*, in which is located a pneumatic

hammer or plunger *c* of any approved type, the front end of the said casing having the usual passage *d* for the butt end of the drill *e*.

Referring now more particularly to my improved attachments, the same includes a main frame 1, that is attached to and is mounted on the front end of the casing *b* and disposed transversely thereof whereby to bring a forwardly extended apertured hub portion 15 of the said frame in longitudinal alinement with the drill shank passage *d* in the casing *b*. The framing 1 also includes a cylinder 16, the opposite ends of which are formed with axial sockets 17—17 70 for receiving the opposite ends of a shiftable valve 3 on which is loosely mounted a piston 2, provided with a central annular groove 20, for receiving the projecting lug 60 of the shiftable or ratchet block 6, presently again referred to.

17^a designates a main inlet for the working fluid, and the same is located centrally over the working cylinder and it communicates with the opposite ends of the said cylinder through the fluid passages 18.

Valve 3, before referred to, is in the nature of a central shaft for the piston, its opposite ends projecting into the sockets at the opposite ends of the working cylinder and each of the said ends has an inlet 30—30 that connects, through the ports or channels 31 with the inlet ports 4—4^a in the opposite ends of the cylinder. Valve 3 at each end has an annular fluid passage 33 and each of the passages 33 connects with a longitudinal fluid passage 34—34, that extends over nearly to the other end of the valve and the end of each of the passages 34 terminates in a radial outlet 35 that opens 90 into the working cylinder or chamber, as is best shown in Fig. 2 of the drawing, by reference to which it will be also seen each end of the valve has another annular groove 36—36 that forms passages for the fluid 95 passing from the main inlet to and through the lateral fluid passages to the working cylinder under the proper adjustments of the valve.

By reason of the peculiar construction and arrangement of the parts constituting the working cylinder and piston, it will be readily apparent by referring to Figs. 1, 2 and 3, that when the piston has traveled to the position shown in Fig. 2, valve port 4^a 110

opens which allows the fluid to pass to the right hand end of the valve 3, (see Fig. 2) to force the said valve 3 back to the position shown in the said Fig. 2, thereby bringing the fluid passage from the main inlet into open communication with the working cylinder at the right hand end of the piston and the other end of the cylinder into open communication with the exhaust. 5.

10 Both ends of the cylinder and the valve are alike and hence after the action just explained has taken place under the movements of the piston in one direction, a like action takes place at the other end by reason 15 of the movement of the piston in the other direction.

Since the piston and the valve travel the same way, it is evident that should there be any friction on the piston or the valve, it 20 will assist in holding the valve open to its work.

For turning the drill, I prefer to use the ratchet mechanism shown and the same includes a ratchet sleeve or bushing 8 that turns in the hub of the main framing and in which the drill shank is slidably held. The ratchet block 6 before referred to is reciprocably held in a socket 61 in the framing and it carries a drop-pawl 10 that engages the ratchet at one side, a second pawl 12 being also provided for engaging the ratchet at the same side, the latter pawl being pivotally mounted on a rocker lever 9 normally held by a spring 13 to pull the pawl 12 back from the ratchet 8. One end of the lever 9 is projected in the path of movement of the ratchet block 6 and is so disposed that as the said block is carried forwardly with the piston 2 (see arrow *x*) 30 the said block engages the lever 9 and thereby throws the pawl 12 to turn the ratchet with the drill in the direction indicated by the arrow *y*, it being obvious from the drawing that as the block 6 is moved in 35 the other direction its pawl 10 engages and moves the ratchet 8 in the same direction, the reciprocal movement of the block 6 under the reciprocating actions of the piston imparts a continuous rotary travel to the 40 drill.

To provide for a simple and expedient assembling of the valve and the piston, one end of the piston cylinder casing is plugged as at 40, and the plug held by a cross pin 41. 45 In this application, I make no claim to the

construction of the chuck and the connections between the reciprocating piston 2 and the drill *e* as that forms the subject matter of my original application filed April 7, 1913, #759,538, of which original application the present one is a divisional part. 60

From the foregoing taken in connection with the drawings, the complete construction, the manner of operation and the advantages of my invention will be readily 65 understood by those skilled in the art to which it appertains.

What I claim is:—

1. A fluid operated engine including a casing having a chamber, said casing having counterbores communicating at one end with said chamber, a reciprocating piston mounted in said chamber, a valve member projecting through an aperture in said piston and projecting into said counterbores of 75 said casing, and means for shifting said valve member by the fluid that operates said piston.

2. A fluid operated engine including a casing having a chamber, said casing having counterbores communicating at one end with said chamber, a reciprocating piston mounted in said chamber, a valve member projecting through an aperture in said piston and projecting into said counterbores of 80 said casing, and means for shifting said valve member by the fluid that operates said piston, said last named means including fluid passages in said casing, other fluid passages 85 in said valve member coöperating with said piston and with said casing passages to control the action of said valve member.

3. A pneumatic engine comprising a casing having a piston chamber, a piston in said chamber, said piston having a bore, a 95 valve member longitudinally movable in said piston bore and in said chamber, and means coöperative with said piston, said valve member, and said casing chamber for automatically effecting the shifting of said 100 valve member according to the position of said piston and thereby control the action of said piston, said last named means including fluid passages in said valve member and in said casing.

CLARK J. SMITH.
